Patented Jan. 19, 1926.

UNITED STATES PATENT OFFICE.

ALBERT DAVID, OF CHICAGO HEIGHTS, ILLINOIS, ASSIGNOR, BY MESNE ASSIGNMENTS, TO DIP-IT INC., OF NEW YORK, N. Y., A CORPORATION OF NEW YORK.

COLORING COMPOSITION.

No Drawing.

Application filed May 21, 1921. Serial No. 471,438.

To all whom it may concern:

Be it known that I, ALBERT DAVID, a citizen of the United States, and a resident of Chicago Heights, Cook County, State of Illinois, have invented an Improvement in Coloring Compositions, of which the following is a specification.

My present invention relates to coloring, dyeing or tinting substances, particularly in liquid or paste form, and also to materials, especially of a saponaceous character, which may be successfully and practically employed as carriers for the dyes employed in the manufacture of the aforesaid liquid or paste, coloring or equivalent compositions. It is an object of the present invention to provide coloring substances of the character specified which shall be uniform in composition, which shall substantially avoid spotting and smearing of the fabrics to which they are applied, and which shall also provide a dye in such a condition that it is already fully dissolved and in such a form as to render the use of such coloring substances highly convenient and economical.

For purposes of example I shall, in the accompanying specification, set forth one illustrative embodiment of my invention, it being, however, clearly understood that my invention is not limited to the illustrative embodiment which is herein described for purposes of illustration only.

For the coloring, tinting or dyeing substance I may use any suitable dyestuff, preferably a water-soluble dye, whether acid, direct or basic. While varying amounts of this dyestuff may be employed, I prefer that the finished composition shall contain about one per cent by weight of the dyestuff.

Intimately mixed with the other ingredients of the coloring composition, particularly the dyestuff, is a saponaceous substance preferably comprising ordinary pure soap such as the soaps known to the trade under the names "Ivory" soap, "Lux", "Fairy" soap, or "castile" soap. This soap serves to give body to the coloring composition, particularly where it is desired, as is preferred, to have the coloring composition in the form of a paste. The soap also serves to exercise a cleansing action on the fabric being colored, dyed or tinted, and serves at the same time to help fix the dyestuff on the fabrics to which it is being applied. While varying amounts of the saponaceous body or

soap may be employed, I prefer to use about one per cent by weight of the soap in the finished composition.

In order to substantially completely dissolve the dyestuff, rather than to provide the same in the form of an undissolved or solid suspension, with consequent spotting and smearing and other disadvantages, I prefer to employ enough of a liquid carrier, such as water, to completely dissolve the dyestuff and to dissolve the soap, or at least to convert the final mixture into a paste if a liquid is not desired. For this purpose I prefer to employ water in an amount, for example, of about sixty-eight per cent by weight of the finished composition. It will be noted that the water and the soap together form a liquid or paste saponaceous body or carrier in which the dyestuff is substantially completely and truly dissolved.

I have discovered that a liquid or paste coloring substance of the character thus far described possesses the undesirable property that it cakes or hardens on exposure, particularly on contact with the air, a condition hardly to be avoided in the ordinary use and manipulation of such coloring substances. In order to avoid this undesirable condition and in order to provide further means for effecting a more or less complete solution of the dyestuff in the finished composition I prefer to employ a hygroscopic substance, preferably in liquid form, such as glycerine, in an amount, for example, equaling about thirty per cent by weight of the finished composition. I find that this substance not only prevents caking and solidification on exposure but even prevents a more or less superficial drying of the composition and prevents also the undesirable insoluble soap film which would otherwise form on the composition, as on exposure to the air, and which would thus interfere with the convenient and successful application of the coloring substance to the fabric to which it is to be applied.

The ingredients specified above are intimately and carefully mixed so that the product is as uniform as possible. For this purpose I prefer even to filter the composition so as to remove insoluble particles of dyestuff or of foreign matter. The finished composition is thus a liquid or paste coloring substance holding the dyestuff in true solution. This result is helped by the pres-

ence of the glycerine, which acts as a partial solvent for the dyestuff, although the dyestuffs generally employed are not as soluble in glycerine as they are in water. However, this additional solubility enables the product to be made up to the desired coloring strength due to the partial solubility of the dyestuff in the glycerine.

The advantages of the present composition are numerous. Due to the dyestuff being present in the composition in the form of a true solution, the product is uniform and may be fully standardized. In this way the uncertain and variable results of the coloring compositions in solid powder or soap form, hitherto employed in the art, are entirely avoided and overcome. The spotting so frequently met with in powder coloring or tinting substances is avoided and the smearing generally resulting from the use of coloring or tinting solid soaps is also avoided.

The composition being in the form of a liquid or paste may be readily packaged in collapsible tubes, which is a distinct advantage since these substances, due to their great coloring power and the undesirability of spreading except on the fabric, should be contained within receptacles from which they can be cleanly and economically distributed. The presence of the hygroscopic substances, particularly the glycerine, the use of which is preferred, assists the water or other liquid carrier in keeping the dyestuff in perfect solution and at the same time by reason of this hygroscopic action prevents the carrier from solidifying and the contents of the tube from caking or hardening. In particular, the glycerine prevents the formation of an insoluble soap film generally consisting of stearic, oleic, or palmitic acid or combinations of the same, which film would interfere with the dispensing of the

liquid or paste from the tube in which it is contained and would also interfere with the successful and uniform application of the coloring or tinting composition to the fabric to which it is to be applied.

The dyestuff being already in true solution and the composition preferably having been filtered before being filled into the tubes, so as to increase its uniformity, the results obtained are uniform and dependable so that a neat, clean job may be made of the coloring or tinting operation by persons, such as housewives, ordinarily unskilled in the manipulation of coloring substances.

The presence of the soap, substantially all in solution, not only lends body to the composition but serves also to cleanse the fabric and to fix the dyestuff on the fabric to which it is being applied. This action of the soap is much facilitated by its being substantially all in solution and by the dyestuff itself being in solution. The soap serves also at the same time to remove any trace of hardness in the water in which the coloring or tinting operation takes place, which hardness would serve to interfere with the fixing of the dyestuff on the fabric.

It is, of course, to be understood that my invention is not limited to the particular embodiment thereof herein shown and described.

What I claim is:

A fluid coloring, dyeing or tinting composition comprising, in combination, a saponaceous body, a liquid carrier, glycerine in sufficient quantity to substantially prevent caking of the mixture on exposure to the air, and a dye dissolved partly in said liquid carrier and partly in said glycerine.

In testimony whereof, I have signed my name to this specification this 18th day of May, 1921.

ALBERT DAVID.
